CLAIM

(57) The ornamental design for a bicycle rim, as shown and described.

DESCRIPTION

FIG. 1 is a front elevational view of a bicycle rim embodying our new design;

FIG. 2 is a rear elevational view thereof; and,

FIG. 3 is an enlarged fragmentary view of the designated portion in FIGS. 1 and 2.

The broken lines are included for the purpose of illustrating boundary lines and form no part of the claimed design.

1 Claim, 3 Drawing Sheets**FIG. 1**

FIG. 2

FIG. 3
